R. B. BENJAMIN.
ILLUMINATING DEVICE.
APPLICATION FILED JAN. 27, 1916.

1,245,083.

Patented Oct. 30, 1917.

Fig. 1.

UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

ILLUMINATING DEVICE.

1,245,083.

Specification of Letters Patent.

Patented Oct. 30, 1917.

Application filed January 27, 1916. Serial No. 74,584.

To all whom it may concern:

Be it known that I, REUBEN B. BENJAMIN, a citizen of the United States, residing at Chicago, in the county of Cook and State of Illinois, have invented new and useful Improvements in Illuminating Devices, of which the following is a full, clear, concise, and exact description, reference being had to the accompanying drawing, 10 forming a part of this specification.

My invention relates to illuminating devices, and more specifically to automobile lamps having concave reflectors.

Among the objects of my invention is to 15 provide an improved device which will prevent the glare, due to the upwardly and forwardly extending rays, and which will redirect these rays forwardly and laterally to furnish the necessary light for illuminating 20 the roadway at the sides of the vehicle and for turning corners.

In the drawings, in which I have shown one embodiment of my invention.

Figure 1 is a vertical transverse section of 25 a lamp on the line 1—1 of Fig. 2:

Fig. 2 is a vertical axial section on the line 2—2 of Fig. 1; and

Fig. 3 is a horizontal axial section on the line 3—3 of Fig. 1.

30 Referring now to the drawings in detail I have shown my invention in connection with a lamp comprising a casing 10, a concave reflector 11 located in the casing, a frame 12 pivoted with respect to the casing 10, a front glass 13 mounted in the frame 12, reflectors 14 and 15 which may be of sheet metal for reflecting forwardly and laterally the direct rays of light which would otherwise escape forwardly and up- 35 wardly in front of the reflector 11, a screen or bar 16 for intercepting the direct rays of light which would otherwise escape forwardly and upwardly in front of the reflector 15, a supporting plate 17 for the reflector 40 14 and 15 and the screen 16, and an electric light 18 suitably supported and located with respect to the reflector 11. The reflector 11 comprises a concave portion 19 which may be parabolic in vertical axial sec- 45 tion so that the rays reflected therefrom will extend substantially in horizontal planes, and a horizontal section of which may be slightly more divergent than a parabola so that the reflected rays will diverge slightly 50 laterally, and a spherical portion 20 in the

rear of the light 18 and substantially concentric with the source of light. The reflector 14 may be formed of sheet metal bent to substantially a V-shape and having its ends secured at 21 to the supporting plate 60 17. The arms of this V are curved slightly as shown at 22 in Fig. 2, and these curved portions 22 are shaped so as to reflect the light which falls on them forwardly and laterally as indicated by the lines A, A', B 65 in Fig. 1. The rear edge 23 of this reflector is shaped so that the reflector will intercept the direct light which would otherwise escape forwardly and upwardly in front of the concave reflector 11, as indicated by the line C, Fig. 2, and the line D, Fig. 3. The reflector 15 is also V-shaped in cross section and is secured at 24 to the plate 17. The rear edge 25 of this reflector is shaped so as to intercept the direct light which would 75 otherwise escape forwardly and upwardly in front of the reflector 14 as indicated by the line E, Fig. 2, and the line F, Fig. 3.

The front edge 26 of the reflector 15 is shaped so as to intercept the direct light 80 which would otherwise escape forwardly and upwardly above the upper edge of the screen 16, as indicated by the line G, Fig. 2. The curved portions 27 of the reflector 15 are shaped and disposed so as to reflect the 85 light which falls on them forwardly and laterally, as indicated by the lines H, H', I, Fig. 1. The support 17 may be cut away as indicated at 27, so as to interfere as little as possible with the rays of light and may be 90 secured to the reflector 11 by having its ends inserted in slots 29 in the reflector, springs 30 secured to the reflector 11 being provided to hold the support in position endwise, these springs yielding to permit the inser- 95 tion of the support.

In use the rays of light falling on the reflector portion 19 are reflected horizontally, as indicated by the lines J, K Fig. 2, the source of light being located in substantially 100 the focus of the vertical parabolic section of the concave reflector, and are caused to diverge laterally slightly as indicated by the lines L, M, Fig. 3, due to the greater divergence of the horizontal section of the 105 concave reflector.

The disposition of the reflectors 14 and 15 is such as to interfere very slightly with the rays reflected from the concave reflector 11, as they are arranged so that their edges 110

are presented to the nearly parallel rays of light from the reflector portion 19, their intersections with planes through the axis of the reflector 11 being substantially parallel to this axis. These reflectors intercept substantially all of the direct light above the horizontal plane and in front of the reflector portion 19 and direct it forwardly and laterally as indicated by the lines A, A', 10 B and H, H', I, Fig. 1, to furnish the necessary light for illuminating the roadway at the sides of the vehicle and for turning corners.

Having thus described my invention, what I claim as new and desire to secure by Letters Patent is:

1. A vehicle light comprising a concave reflector having its axis horizontal, means for supporting a source of light in said reflector, and a reflector device mounted inside of said concave reflector adjacent and in front of said source of light, said reflector device comprising a reflecting surface having a curved rear edge lying in the surface 25 of a cone having its apex in the light center and the outline of its base defined by the front edge of said concave reflector, said reflector device comprising also a second reflecting surface having a curved rear edge 30 lying in the surface of a cone having its apex in the light center and the outline of its base defined by the front edge of said first reflecting surface.

2. A vehicle light comprising a concave reflector having its axis horizontal, means for supporting a source of light in said reflector, and a reflector device mounted inside of said concave reflector adjacent and in front of said source of light, said reflector 40 device comprising a reflecting surface having a curved rear edge lying in the surface of a cone having its apex in the light center and the outline of its base defined by the front edge of said concave reflector, said reflector 45 device comprising also a second reflecting surface having a curved rear edge lying in the surface of a cone having its apex in the light center and the outline of its base defined by the front edge of said first reflecting surface, said reflecting surface being 50 curved in transverse cross section.

3. A vehicle light comprising a concave

reflector having its axis horizontal, means 55 for supporting a source of light in said reflector, and a reflector device mounted inside of said concave reflector adjacent and in front of said source of light, said reflector device comprising a reflecting surface having a curved rear edge lying in the surface 60 of a cone having its apex in the light center and the outline of its base defined by the front edge of said concave reflector, said reflector device comprising also a second reflecting surface having a curved rear edge 65 lying in the surface of a cone having its apex in the light center and the outline of its base defined by the front edge of said first reflecting surface, the cross sections of said reflecting surface being in the form of inverted V's.

4. A vehicle light comprising a concave reflector having its axis horizontal, means for supporting a source of light in said reflector, and a reflector device mounted inside of said concave reflector immediately 75 adjacent and in front of said source of light, said reflector device comprising a reflecting surface having a curved edge lying in the surface of a cone having its apex in said light center and the outline of its base defined by the front edge of said concave reflector, the intersections of said reflecting surface with planes through the axis of the reflector being parallel to the axis.

5. A vehicle light comprising a concave 85 reflector having its axis horizontal, means for supporting a source of light in said reflector, and a reflector device mounted inside of said concave reflector immediately 90 adjacent and in front of said source of light, said reflector device comprising a reflecting surface having a curved edge lying in the surface of a cone having its apex in said light center and the outline of its base defined by the front edge of said concave reflector, the intersections of said reflecting surface with planes through the axis of the reflector being parallel to the axis, the intersections of said reflecting surface with planes transverse to the axis of the concave reflector 95 being substantially inverted V's.

In witness whereof, I have hereunto subscribed my name.

REUBEN B. BENJAMIN
